VOTING MACHINE

Ransom F. Shoup, Ardmore, Pa., assignor to The
Shoup Voting Machine Corporation, Philadelphia, Pa., a corporation of Delaware

Application February 21, 1941, Serial No. 379,978

4 Claims. (Cl. 235—55)

This invention relates to voting machines and more especially to voting machines of the type disclosed in Shoup et al. Patent No. 2,054,102.

In certain States, the election laws provide that with respect to certain offices, for example, representation in the general assembly, each elector has the right to cast from one to three ballots for any candidate and also, the voter has the right to distribute his three votes in any manner that he may desire among one to three candidates of his choice. Such provision is for the purpose of properly proportioning and balancing the relative strength of the political parties as it may be indicated in the general assembly. He may cast his entire three votes for one candidate; he may cast two votes for one candidate and his remaining vote for a second candidate; he may cast one and one-half vote for each of two candidates; or he may cast a single vote for each of three candidates. He may limit his choice of candidates to a single party or he may split his vote among the candidates of two or more parties.

An object of this invention is to equip the Shoup type voting machine with mechanism to enable it to be used for cumulative voting according to the election laws above referred to.

Other objects, novel features and advantages of this invention will become apparent from the following specification and accompanying drawings, wherein:

Fig. 1 is a fragmentary rear elevation of a Shoup type voting machine embodying the invention;

Fig. 2 is a horizontal section substantially on the line 2—2 of Fig. 1;

Fig. 3 is an elevation partly broken away of the main interlock of a Shoup type voting machine taken substantially on the line 3—3 of Fig. 2;

Fig. 4 is an enlarged fragmentary view substantially on the line 4—4 of Fig. 1, and

Fig. 5 is a section on the line 5—5 of Fig. 4.

In this specification, reference will be made to certain mechanisms fully described and explained in said Patent No. 2,054,102, and Shoup Patent No. 2,191,086 and with respect to such mechanisms the same reference characters will be used as are used in said patents.

A plurality of columns of spindles 38 extend through and between a vertical partition plate 39 and a plurality of vertical supporting members 40 and are supported for rotation as described in said patents. Each spindle is equipped with an operating handle 30 and a counter C (of the type illustrated in Shoup Patent No. 2,140,336) merely an indication of which appears in the drawings, is associated with each spindle 38. On each spindle are provided arms 59 and 59' between which extends a rod 59b. Each

spindle is limited to oscillation between voted and unvoted position through an arc of predetermined extent by engagement of the arm 59 with the next lower spindle in the manner disclosed in said Shoup Patent No. 2,054,102, particularly in Fig. 25. A pull strap 61 is attached to each rod 59b and leads to the main interlock 42 which is of the same construction as described in Shoup Patent No. 2,191,086. In this interlock 10 are provided a plurality of cylindrical rollers 62, certain of which are tubular for the purpose of receiving pins 63 extending through apertures in the interlock casing for the purpose of fixing said rollers against movement relative to the casing. 15 The pull straps 61 pass between the rollers and are provided with wedges 64 for spreading apart the rollers.

At least two of the straps 40 are provided with vertically spaced pins or studs 401 having heads 20 402. A plate is supported between corresponding pairs of pins for horizontal reciprocation, these plates being designated respectively 403a, 403b and 403c. Each plate is provided with a plurality of vertical rows of square apertures 405 through each of which extends a spindle 38. To each plate is attached a pull strap 61' leading to the auxiliary interlock 42' in which are provided cylindrical rollers 62', certain of which are tubular for the purpose of receiving pins 63' extending through apertures in the interlock casing for fixing said rollers against movement relative to said casing. Each draw bar 61' passes between a pair of rollers and is provided with a wedge 64' for spreading apart the rollers. The horizontal 30 extent of each aperture 405 is sufficient to permit horizontal movement of the plate to move a head 64' between rollers 63'.

On each spindle 38 is fixed an arm 406 having a horizontal stud or pin 407, each pin projecting into an aperture 405. In the unvoted position of a spindle, its arm extends downwardly to the left. The height of each aperture 405 is sufficient to permit the extent of rotation of the spindle 38 necessary to effect actuation thereof 45 from its unvoted to its voting position. A spring 408 is attached to each plate for the purpose of biasing it rightward.

In the wall 10 is provided a vertical column of personal choice slots 139 with a slidable closure 50 140 for each slot. In back of the slots is a guide 141 over which passes a sheet of paper 142 from a feed roller 143 to a take-up roller (not shown). A yoke 150 pivotally supported on a rod 150a is rotated counter-clockwise from the position 55 shown in Fig. 2, by movement of any closure 140 to its open position and when actuated, is returned to its original position upon return of the machine to curtain open position by means (not shown) but fully disclosed in said Shoup 60 et al. Patent No. 2,054,102. The yoke 150 coacts

with mechanism (not shown) to advance the strip 142 a predetermined distance for each actuation of the yoke.

A vertical plate 150c of the shape shown in Fig. 2 is provided with a vertical series of apertures constituting guideways for links 161 which, at one end, are attached to arms 160 pivotally supported by the rod 150a mounted in brackets 150b attached to the plate 150c, and each link is provided with a pin 61a connected to an interlock strap 61. Each of the arms 160 is provided with a head 160' projecting into a slotted channel shaped runner 222 having a right-angle extension attached to a slide 223 supported by the wall 10. Each slide is in alignment with a personal choice slot closure 140 so that movement of a personal choice slot closure to open position swings the arm 160 counterclockwise with consequent leftward movement of the corresponding link 161 and its associated interlock strap 61 to bring the head 64 thereof between rollers 62. Restoration of any actuated arm 160 and the corresponding closure 140 is effected by the mechanism for that purpose described in Shoup et al. Patent No. 2,191,086.

Each of the plates 403a, 403b and 403c is provided with a right angle flange 409 projecting into the path of the same number of pins 61a as there are horizontal rows of spindles projecting through the plate. Leftward movement of any one of the pins 61a results in leftward movement of the plate, the flange 409 of which it engages.

In the set-up of the machine herein disclosed, the plate 403a, as well as each of the other two plates, is equipped with three vertical rows of apertures 405 with three apertures in each row. The arrangement of the apertures is such that with the spindles in unvoted position and the plate in its rightmost position, the left hand vertical side of each aperture is engaged near its bottom by a pin 407 and the head 64' is out of engagement with the rollers 62'. Upon actuation of any spindle to voting position, the spindle turns clockwise with consequent elevation of the pin 407 through an arc, the extent of which is limited by the extent of rotation of the spindle from voted to unvoted position. The arrangement of the arm 405 on the spindle is such that the arc through which the pin 407 travels locates the pin at a slightly higher level than the axis of the spindle so that after a spindle has been actuated into voted position, the pull exerted on the pin 407 by the spring 408 through the medium of the plate tends to advance the spindle beyond voted position rather than to restore it to unvoted position (Fig. 1, Socialist column, 4th spindle). However, because spindle cannot proceed beyond its voted position, the spring tends to maintain the spindle in voted position and oppose return of it to unvoted position. The leftward movement of the plate is sufficient to bring the corresponding head 64' between two rollers 63'. The plate is released for rightward movement by counterclockwise operation of the spindle either by the voter or by the spindle restoring mechanism operative upon operation of the machine from curtain closed to curtain open position as fully described in said Patent No. 2,054,102, but not herein illustrated. The arrangement of the rollers 63' is such that only one wedge 64' can be drawn between the rollers 63'. Therefore, actuation of one plate locks out the remaining plates.

Actuation of any one of the top three personal choice slot closures 139 results in leftward move-

ment of the plate 403a through the medium of the associated slide 223, runner 222, arm 160, link 161 and pin 61a. Similarly, actuation of any of the middle three personal choice slot closures results in leftward movement of the plate 403b and also opening of any of the bottom three personal choice slot closures results in leftward movement of the plate 403c. Whichever plate is moved leftward, the remaining two are locked out as previously described.

That section of the main interlock into which extend the interlock straps 61 of the upper three rows is set to permit actuation of only one spindle of the upper three rows or one of the upper three personal choice slot closures 140, or as is more commonly expressed is set to vote 1. This is accomplished by the use of the proper number of movable rollers 62 between fixed rollers, that is rollers through which pins 63 extend, to permit the introduction only of a single wedge 64 between the rollers.

The section of the main interlock into which extend the interlock straps 61 of the middle three rows of spindles and the middle three personal choice slot closures is set to vote 2 while that portion of the main interlock into which extend the interlock straps 61 of the lower three rows and the lower three personal choice slot closures is set to vote three. The middle and bottom interlock sections are set by proper arrangement of movable rollers between the fixed rollers as above explained.

As indicated in Fig. 1, each set of three spindles in each column is allocated to the same group of candidates and in a general election, each column of spindles is allocated to a single political party. The counter associated with each spindle is advanced one digit for each spindle actuation but each digit of a counter of the upper three rows is counted as three votes for a candidate while each digit of a counter in the middle three rows is counted as a vote and a half for a candidate and each counter digit in the bottom three rows is counted as a single vote for a candidate.

A voter may cast a ballot for candidate G by actuating either the first, fourth or seventh spindle of the Socialist column. If he actuates the first spindle, he moves the plate 403a leftward, thereby actuating the auxiliary interlock 42' to lock out the plates 403b and 403c. Also, he simultaneously draws a head 64 between rollers 62 of the top section of the main interlock. As the top section of the main interlock is set for vote one only, the voter cannot actuate any other spindle in the top set of three rows nor any of the top three personal choice slot closures 140. Also, because of the fact that the plates 403b and 403c are locked out by the auxiliary interlock, he cannot actuate any of the spindles in the middle and bottom sets nor any of the personal choice slot closures from four to nine. The voter has thus cast his entire quota of votes for G. The voter may cast a ballot for an unlisted candidate by opening one of the top three personal choice closures 139 and writing in the candidate's name on the strip 142 rather than actuating a spindle. In the event that he actuates a personal choice slot closure he locks out the entire set of spindles and all the remaining personal choice slot closures as above described.

If the voter actuates the second spindle allocated to G, as indicated in Fig. 1, he moves the plate 403b leftward, thereby locking out the plates 403a and 403c in the manner previously described. He also draws a wedge 64 between

rollers 62 of the auxiliary interlock. However, as the auxiliary interlock is set for vote 2, the voter may actuate another spindle, for example, the second spindle allocated to candidate C. After actuation of the second spindle, the voter cannot actuate any further spindles of the second three rows nor can he actuate any personal choice slot closure from four to six. Likewise, he cannot operate any of the spindles or personal choice slot closures in the top and bottom groups. With this arrangement, the voter has divided his ballot between two candidates and has given one and one-half votes to each. A voter may cast one and one-half votes for each of two unlisted candidates by actuation of two of the personal choice slot closures from four to two and writing in the candidate's name instead of actuating two spindles and such actuation of the personal slot closure locks out the remaining personal choice slot closure as well as all the spindles.

If the voter actuates the third spindle allocated to the candidate G, he actuates the plate 403c leftward in the manner previously described, thereby actuating the auxiliary interlock to lock out the plates 403c and 403b. Also, since the bottom portion of the main interlock is set for vote 3, he may actuate two additional spindles of the bottom group or two personal choice slot closures. The spindles and personal choice slot closures of the upper two groups are locked out in the manner previously described. Through the medium of the bottom set of spindles and personal choice slot closures, a voter may cast one ballot for each of three candidates, or may cast one ballot for one candidate and two ballots for another candidate. He may cast his two ballots for the same candidate by first actuating the spindle assigned to that candidate and then opening a personal choice slot closure and writing in the candidate's name.

A voter may cast his vote for one or more candidates not listed on the official ballot and may divide his three votes among such candidates as he sees fit through the medium of the personal choice mechanism. For this purpose, he may utilize one personal choice slot of the top three or two personal choice slots of the middle three or three personal choice slots of the lower three. The location vertically on the strip 142 of the written-in candidate's name determines whether such write-in is counted as one, one and one-half or three votes for the candidate.

I claim:

1. In a voting machine having a plurality of spindles and means for limiting the extent of rotation of each spindle between voted and unvoted position, mechanism for conditioning said machine for cumulative voting with said spindles divided into a plurality of multiple-spindle groups, said mechanism comprising a plate for each group supported for reciprocation transversely of the axes of said spindles between a first position and a second position and biased for movement into said first position, said plate having a plurality of surfaces perpendicular to its direction of reciprocation, a crank pin carried by each spindle for engagement with a said surface of a plate to effect movement of said plate from its first position to its second position and partially back toward its first position under the

influence of said biasing means upon movement of said spindle from its unvoted position to its voting position, said crank pin being so arranged with respect to the spindle axis that in unvoted

- 5 position of the spindle the pin lies on one side of a line passing through the spindle axis parallel to the direction of reciprocation of said plate and lies on the opposite side of said line in the voted position of said spindle, an interlock for the set of plates responsive to actuation of one plate to prevent actuation of any remaining plate, and an individual auxiliary interlock for the group of spindles associated with each plate effective upon actuation of a predetermined number of spindles
- 10 15 of said group to prevent actuation of any remaining spindle of said group, each auxiliary interlock being arranged to permit the actuation of a number of spindles of its group different from any other group.
- 20 2. In a voting machine, the combination according to claim 1 wherein the spindles are horizontal and the plates are supported for horizontal reciprocation.

3. In a voting machine having a plurality of 25 spindle members and means for limiting the extent of rotation of each spindle member between voted and unvoted position, mechanism for conditioning said machine for cumulative voting with said spindle members divided into a plurality of multiple-spindle member groups, said mechanism comprising a plate for each group supported for reciprocation transversely of the axes of said spindle members between a first position and a second position and biased for 30 movement into said first position, said plate having a plurality of surfaces perpendicular to its direction of reciprocation, a crank pin carried by each spindle member for engagement with a said surface of a plate to effect movement of said plate from its first position to its second position and partially back toward its first position under the influence of said biasing means upon movement of said spindle member from its unvoted position to its voting position, said crank pin being so 35 arranged with respect to the spindle member axis that in unvoted position of the spindle member the pin lies on one side of a line passing through the spindle member axis parallel to the direction of reciprocation of said plate and lies on the opposite side of said line in the voted position of said spindle member, a group of personal choice slide members for each group of spindle members, means for effecting movement of a plate from its first to its second position upon actuation of a 40 personal choice slide member allocated thereto, an interlock for said group of plates responsive to actuation of one plate to prevent actuation of any remaining plate, and an individual auxiliary interlock for the set of spindle and slide members associated with each plate effective upon actuation of a predetermined number of members of said set to prevent actuation of any remaining member of said set, each auxiliary interlock being arranged to permit the actuation of a number of 45 spindle and slide members of its set different from any other set.

4. In a voting machine, the combination according to claim 3 wherein the axes of said spindle members are horizontal and said plates are supported for horizontal reciprocation.

RANSOM F. SHOURP.
